DUCTOR ROLL TIMER

Filed March 31, 1930

UNITED STATES PATENT OFFICE

WILLIAM G. HUMPHREY, OF TORONTO, ONTARIO, CANADA

DUCTOR ROLL TIMER

Application filed March 31, 1930. Serial No. 440,573.

This invention relates to brake devices for rotating shafts or axles, and has reference more particularly to such devices as employed in connection with inking mechanisms of printing presses or the like to control the rotation of the ductor roll.

The ductor roll of an inking mechanism of this type is generally mounted in brackets which are pivoted to the frame of the press, and is given an oscillatory movement in an arcuate path between the fountain roller from which it receives a film of ink and the distributing roller or plate to which the ink is transferred. Both the fountain roller and the member to be inked are preferably power driven, and the ductor roll is rotated by rolling contact therewith. In the absence of some means for controlling the free rotation of the ductor roll during its oscillatory movement from one of these members to the other, considerable wear and abrasion of the composition of which the rolls are formed would result from the rather violent contact of the spinning ductor roll with these members. Furthermore, when the ductor roll is permitted to resume contact with the fountain roller and ink distributing plate or roller at random, there usually results an uneven distribution of the ink, resulting in impression areas of different intensities. This defect is particularly noticeable and objectionable in color work.

It is an object of the present invention to provide a novel brake device of the type described which is adapted to prevent the spinning or racing of the ductor roll.

Another object is to provide such a device which may be actuated during the oscillatory movement of the ductor roll from the fountain roller to the ink receiving surface to frictionally engage the ductor roll shaft, so that the ductor roll will be so timed as to present a new portion of its surface to a freshly inked surface of the fountain roller upon each oscillation, thus insuring an even or uniform distribution of ink to the distributing members.

Other objects and features of novelty will be apparent from the following description when read in connection with the accompany-

ing drawing in which one embodiment of my invention is illustrated by way of example.

In the drawing:

Figure 1 is a view in elevation of a portion of a flat bed printing press, showing the relation of the ductor roll timer to the inking mechanism thereof; 55

Figure 2 is a vertical central cross-sectional view of the timer applied to the ductor roll shaft; 60

Figure 3 is a transverse cross-sectional view taken on line 3—3 of Fig. 2; and

Figure 4 is a fragmentary cross-sectional view taken on line 4—4 of Fig. 2. 65

In Fig. 1 of the drawing, the numeral 10 designates generally a printing press of the flat bed type provided with the frame 11, supporting members 12 and the horizontally reciprocating bed 13. At the end of the bed 13 there is provided an ink plate 14 which is adapted to oscillate beneath the form rollers 15 in the conventional manner. The press is provided with the usual ink fountain 16 and fountain roller 17, both carried by the bracket 18. Journalled in the frame 11 of the press is the transverse shaft 20 upon each end of which is mounted one end of a bracket 21. Bearings 22 are formed on the free ends of the brackets 21 for the reception of the ends of the ductor roll shaft or axle 23. The usual ductor roll 25 is mounted upon the shaft 23 and, upon pivotal oscillation of the brackets 21, it is moved between the full line position shown in Fig. 1, where it is in contact with the ink plate 14, and the dotted line position 26, in which it is in rolling contact with the fountain roller 17. 70 75 80 85

The fountain roller 17 is driven in the usual manner by means not shown, and the ink plate 14 is oscillated by the conventional and well-known mechanism. 90

Although the ductor roll 25, as illustrated and described herein, is designed to transfer the ink from the fountain roller 17 to the ink plate 14, it will be understood that my invention is applicable to an inking mechanism wherein the ductor roll is adapted to transfer the ink from a fountain roller to one of the distributing rollers of the press. 95

The ductor roll 25 is adapted to rotate in 100

rolling contact with the fountain roller 17 and the ink plate 14 at either end of its path of movement and, upon leaving either of these two members during its oscillatory movement about the shaft 20 as a center, there would be a tendency for the ductor roll to spin freely. Then, upon resuming contact with either of these members, the rotational movement would be halted abruptly and damage to the composition of the ductor roll 25 or the fountain roller 17 would ensue. Furthermore, if this free rotation of the ductor roll were permitted, the ductor roll would contact with the fountain roller 17 and the ink plate 14 at random points having no relation to the areas of previous contact by the ductor roll. This would obviously cause an uneven distribution of ink on the ink plate or distributing roller and would result in streaking or variations in intensity of the impression.

Thus, in order to prevent the free rotation of the ductor roll during its oscillatory movement and to so time the rotation of the ductor roll that it will present a new portion of its surface to the fountain roller upon each oscillation, there is provided the brake or timing device designated generally by the numeral 30. This timer 30 is provided with a sleeve-like body member 31 which is adapted to surround the ductor roll shaft 23 and to be carried thereby. This body member 31 is provided with an extension 32 and has an elongated slightly curved surface 33 the function of which will be later described. The internal diameter of the sleeve-like body portion 31 is larger than the diameter of the shaft 23, and the interior surface of this member is generally cylindrical but is provided with the flattened area 34 upon one side thereof. A flexible brake band 35, preferably formed of sheet metal and provided with a lining 36 formed of a suitable frictional material, is disposed within the bore of the member 31, so as to partially surround the periphery of the shaft 23. One end of the brake band 35 is secured to the body member 31 by means of the rivets or other securing means 37. The other end of the brake band 35 is provided with the rod 38 which passes laterally there-through and the ends of which are disposed in the sockets 39 of the rings 40. Each of these rings 40 are rotatably seated in an annular depression 41 formed in either side of the sleeve-like portion 31 and are adapted to closely surround the shaft 23.

A yoke member 42 is provided with arms 43 which are adapted to receive between them the body member 31. The arms 43 are recessed to receive the shaft 23 and are adapted to be rigidly secured to the rings 40 by means of the screws 44. It will thus be seen that rotation of the yoke member 42 about the shaft 23 relatively to the body member 31 in a clockwise direction, as seen in Fig. 2, will cause the brake band 35 to tighten upon the

shaft 23, thus increasing the friction between the brake device and the shaft.

The body portion of the yoke member 42 is designed to carry an adjustable contact arm 45 which is provided with a roller 46 journalled in its outer end, and is secured to the yoke 42 by means of the screw 47 which is adapted to pass through the slot 48 in the arm 45 and is selectively threaded in any one of a plurality of openings 49 in the yoke. The body portion of the yoke 42 is cut away at its forward edge as at 50 to provide clearance for the roller 46 in the retracted position of the arm 45. In order to rigidly retain the arm 45 in its adjusted position, there is provided near the rear edge of the body portion of the yoke 42 the block 51, through which is threaded the set screw 52 which is adapted to engage the rear end of the arm 45 as at 53. The set screw 52 is adapted to be locked into position by means of the nut 54.

Referring to Fig. 1 of the drawing, there is provided a bracket 55 which is mounted upon the frame 11 as at 57, and is formed upon its outer end with the arcuate cam surface 56. The cam surface 56 is concentric with the bearing surface 33 of the brake member and forms a cooperating guide surface therewith to prevent rotation of the brake member about the shaft 23 of the ductor roll.

The cam surface 56 is of such length that in the uppermost position of the ductor roll when it is in contact with the ink receiving surface of the distributor plate or roller, the roller 46 of the contact or actuating arm 45 is not in contact with the cam surface. When the ductor roll 26 is in its lowermost position in contact with the fountain roller 17, the guide surface 33 of the body member 31 of the brake has cleared the lower end of the cam surface 56 sufficiently to permit a slight rotation thereof to release the pressure of the brake upon the ductor roll shaft. As soon as the ink plate 14 has been retracted and the ductor roll 26 starts its movement toward the fountain roller 17, the roller 46 comes in contact with the cam surface 56, and the yoke member 42 is rotated relatively to the body member 31, thus tightening the brake band 35 upon the shaft 23 and effectively preventing or diminishing the rotation thereof. Instead of the attaching means 57, any suitable means may be provided to adjust the cam 56 about the shaft 20 as a center, to properly position the cam with respect to the movements of the ductor roll.

By the proper adjustment of the arm 45, relatively to the yoke member 42, the tension of the brake member may be regulated with great accuracy so that just enough rotation of the ductor roll is permitted in order to time the contact thereof with the fountain roller and distributor member to insure an equal and uniform distribution of the ink to the various rollers. Contact of the ductor

roll with the fountain roller may be attained the proper instant by starting the press, noting the areas of contact of the ductor roll and the fountain roller and adjusting the effective length of the arm 45 by means of the set screw 52 until the ductor roll is timed to make contact at the proper instant.

It will thus be seen that there is provided by means of my invention a device which will 10 permit the free rolling contact of the ductor roll with the fountain roller and ink distributor members, but which will control the rotation of the ductor roll during its oscillatory movement from one of these members 15 to the other, so as to time its rotation with respect to the movements of these members in order to insure smooth operation and uniform distribution of ink.

Various changes and modifications may be 20 made in the embodiment shown and described herein, without departing from the scope of my invention as defined by the following claims.

Having thus described the invention, what 25 is claimed as new and desired to be secured by Letters Patent is:

1. In an inking mechanism for printing presses or the like, including a fountain roller, a member to be inked, and a ductor roll 30 mounted on an axle so as to oscillate bodily between said fountain roller and said member and to rotate in rolling contact therewith; in combination, a brake member carried by said axle and comprising a body portion, a yoke 35 portion movable relatively to said body portion, a flexible band connected at its ends with said body portion and said yoke portion respectively, means carried by the frame of the press for moving said yoke portion relatively to said body portion to cause said band to grip said axle to control the rotation thereof.

2. In an inking mechanism for printing presses or the like, including a fountain roller, a member to be inked, and a ductor roll mounted on an axle so as to oscillate bodily between said fountain roller and said member and to rotate in rolling contact therewith; in combination, a brake device carried by said 50 axle and comprising a sleeve-like member having a guide surface adapted to surround said axle, a flexible brake band disposed between said member and said axle and secured at one end to said member, a pair of rings rotatably disposed at each side of said member, the opposite end of said band being pivotally secured at each side thereof to one of said rings, a brake actuating yoke member having a body portion and a pair of arms 55 adapted to receive said sleeve-like member between them and perforated for the reception of said axle, said rings being rigidly secured to said arms, an extensible arm projecting from the body portion of said yoke and provided with anti-friction means at the end

thereof, and a cam adjustably mounted upon the frame of the press and adapted to cooperate with said guide surface of said sleeve-like member to prevent rotation thereof and to contact with said anti-friction means to actuate said brake applying yoke.

3. A device as set forth in claim 2 in which said extensible arm is provided with a slot, attaching means is passed through said slot and selectively secured at one of a plurality of points in said yoke member, and abutment means are provided for said arm comprising a set screw and locking means therefor.

In testimony whereof I hereunto affix my 80 signature.

WILLIAM G. HUMPHREY.
